UNITED STATES PATENT OFFICE.

RALPH KROEHL, OF WARREN, OHIO.

COMMUTATOR.

Application filed January 30, 1928. Serial No. 250,603.

This invention relates to commutators and to a method of making the same. It has become highly desirable to use molded commutators for electric motors, especially motors of the smaller horse power type. It is essential that such commutators possess high insulating properties and will withstand the heat generated in service as well as being capable of maintaining their integrity of construction under all conditions of use. Various attempts have been made heretofore in the art to provide molded commutators using plastic setting materials, but these have not proved satisfactory, as they disintegrate under the bursting strain to which the commutators are subjected in service. In other types of plastic material bodies there is an objectionable feature that the body is softened under heat permitting the commutator segments to become loosened and thus destroy the effectiveness of the structure.

Objects of my invention are to provide an improved molded commutator wherein the material of the body is of a metallic nature; to provide a commutator formed with a body of metal in which the commutator segments are secured; and to provide a method of constructing such commutators.

With these and such other objects in view as will be apparent from the description, the invention resides in the novel construction, combination, and arrangement of parts as well as the method hereinafter described and claimed and illustrated in the accompanying drawings whereof

Figure 1 is an end elevation of a vertical type commutator as mounted on an armature shaft.

Figure 2 is a vertical section therethrough on the line 2—2 of Figure 1.

Figure 3 is a rear face elevation of one of the commutator segments employed.

Figure 4 is an end elevation of a horizontal type commutator as mounted on an armature shaft.

Figure 5 is a vertical section taken therethrough.

In detail, the vertical type commutators comprise an annular series of commutator segment bars 5, of copper or other suitable metal, having vertically plane outer faces for brush contact with the brushes 6 and 7, the segments being spaced apart by strips 8. The body of the commutator to which

these segments and insulating members are attached in the disclosed embodiment consists of a molded body 9 of type metal, this material being best adapted for the purposes 60 of the invention and being the preferred material employed in the formation of the bodies. The rear face of each commutator segment is formed with an undercut recess 10 for receiving a corresponding head 11 extending from the body 9 when the metal is cast into the recesses, thus providing a rigid connection between the commutator segments and the body. Interposed between the body 9 and the rear face of each commutator bar is an insulating shield 12 formed of any suitable material such as asbestos, baked on enamel, or varnish, or any suitable insulating medium which is applied as a coating or backing sheet to the inner 75 faces of the commutator segments before the body 9 is molded or cast in place. Suitable means are provided in the type metal body 9 such as an inset securing collar 13, or any preferred fastening element, for attaching 80 the commutator to the armature shaft 14. The fastening element 13 may be dispensed with, and it is within the province of the invention, to mold the body 9 in a suitable manner to enable its use as the sole fastening means for attachment to the armature shaft.

In the horizontal type commutator, as shown in Figures 4 and 5, the commutator bars or segments 15 have their inner portions embedded in the body 16, which is, of course, formed of molded type metal. In this form of the invention the contact brushes 16 and 17 engage horizontally against the outer contact faces of the commutator bars. As in the vertical type, the commutator segments 15 are arranged in an annular series being spaced apart by insulating members, comprising mica strips 18 and the outer contact surface of each segment is 95 raised slightly above the outer peripheral face of the type metal body 16 as best shown in Figure 5. Each of the commutator bars 15 is undercut at each end to form a recess and to provide an anchor head 19 which is 105 embedded in the body of the commutator. As in the vertical type, a backing for insulating the covering 20 is positioned over the entire area of the assembled commutator segments and insulating strips which is intended to be covered by a type metal body. This insulating backing is of any suitable 110

material which is adapted for the purpose and may be formed of asbestos, enamel, or varnish, etc., so long as it possesses the requisite insulating properties.

5 In both types of commutator, the insulating members which are disposed between the series of segments are of co-extensive area with the segments and are of identical configuration so that the segments and insulating strips are positioned side by side to form an even surface at their inner faces for reception of the backing sheet of insulating material 12 or 20 as the case may be. This arrangement may be varied as desired.

10 15 The method of constructing these commutators is carried out by properly assembling the commutator segments and their interposed insulating strips in a jig and tightening the same in position. The insulating backing 12, or 20 as the case may be, is then applied over the inner faces of the assembled segments and insulating strips, care being taken to see that it entirely covers every portion of the commutator segments and insulating strips which are to be embedded or in contact with the body of type metal. After this insulating backing has been applied, a sufficient quantity of melted type metal is poured or cast into the form and in the process of molding the metal will, of course, flow into the recesses formed by under-cutting the inner portions of the respective segment bars, thus filling all the recesses and engaging around the anchoring tongues whereby when the metal body is cooled and hardened, the commutator segments will be firmly embedded in the type metal body. The fastening element 13, shown in Figure 2, may be positioned in the jig at the time 20 25 30 35 40 45 the commutator segments are assembled and before pouring of the type metal body.

The resulting structure produces an extremely durable, strong, rigid commutator having a body of metal which is capable of resisting any bursting strain to which the commutator may be subjected. Any developed heat tends to distribute substantially uniformly over the entire body of the commutator and the metal will not soften. The commutator segments are held rigidly in position and any disalignment or relative dislocation therebetween is absolutely elimi-

nated. Type metal has the peculiar characteristic of expanding slightly upon cooling so that the metal is forced by internal pressure in the molecular structure of the metal itself into effective engagement within the recesses formed in the embedded portions of the segment bars.

55 60 In compliance with statute, I have described one complete embodiment as using type metal, but I may equally well employ any alloy, metal or suitable material which will fulfill the purposes of the invention.

65 While I have illustrated and described in this form of the invention the best means I have thus far devised for carrying it into effect, I desire it to be understood that the invention is not limited thereby, but that any desired changes and modifications may 70 be made in the structural detail as will fall within the scope of the invention as claimed.

I claim:

1. A commutator comprising commutator bars embedded in a body of metal molded 75 thereon and insulated therefrom.

2. A commutator comprising metal commutator bars insulated and embedded in a body of type metal molded thereover.

3. A commutator having a molded body 80 of type metal.

4. A commutator comprising commutator bars spaced apart by insulating members, an insulating backing over said bars and insulating members, and a body of metal molded 85 around portions of said bars for anchoring said bars to the body.

5. The method of making a commutator, which consists in embedding commutator bars having an applied insulating material 90 thereon, in a body of molten metal and cooling the metal to form the commutator.

95 6. The method of making a commutator, which consists in arranging commutator bars circumferentially with interposed insulating strips between the respective bars, applying an insulating covering over the inner portions of said bars and insulating members, and pouring molten metal into the interior of the assembled structure to form 100 a body on cooling.

In testimony whereof I affix my signature.

RALPH KROEHLER.
